UNITED STATES PATENT OFFICE.

CHARLES FORTH, OF OTTAWA, ONTARIO, CANADA, ASSIGNOR TO THE NATIONAL CASH REGISTER COMPANY, OF DAYTON, OHIO, A CORPORATION OF OHIO, (INCORPORATED IN 1906.)

RAILROAD-TICKET-ISSUING MACHINE.

1,153,299.

Specification of Letters Patent. Patented Sept. 14, 1915.

Application filed October 31, 1913. Serial No. 798,567.

To all whom it may concern:

Be it known that I, CHARLES FORTH, a citizen of the United States, residing at Ottawa, in the county of Carleton and Province of Ontario, Canada, have invented certain new and useful Improvements in Railroad-Ticket-Issuing Machines, of which I declare the following to be a full, clear, and exact description.

10 The principal object of this invention is to provide a machine for use in offices of public service corporations such as railroads, steam ship and traction lines, which machines are arranged to issue tickets to various 15 destinations traversed by the different lines and automatically accumulate the totals of the fares as the tickets are issued and also to record upon a record strip the destination of each ticket issued and the number 20 of tickets issued to such destination.

With these and incidental objects in view, the invention consists in certain novel features of construction and combinations of parts the essential elements of which are 25 set forth in appended claims, and a preferred form of embodiment of which is hereinafter described with reference to the drawings which accompany and form part of this specification.

30 Of said drawings, Figure 1 is a side elevation partly in section of the improved machine. Fig. 2 is a front elevation of the ticket issuing mechanism. Fig. 2^a is a detail view of the mechanism for operating the inking devices. Fig. 3 is a front elevation of the indicating mechanism for indicating the destination to which the ticket is to be issued. Fig. 4 is a front elevation of the 35 registering mechanism. Fig. 5 is a side elevation of the registering mechanism with the casing therefor in section. Fig. 6 is a top plan view of the inking mechanism. Fig. 7 is an enlarged side view of one of the destination devices. Fig. 8 is an end 40 view of two of the adjacent destination devices. Fig. 9 is an enlarged view partly in section of the ticket severing mechanism. Fig. 10 is a bottom plan view of adjacent 45 destination devices. Fig. 11 is a detail view of the consecutive numbering devices carried by each destination device. Fig. 12 is an enlarged view of the operating head for the destination devices. Fig. 13 is a side view of Fig. 12. Fig. 14 is an enlarged sectional view of the feed rolls for the ticket strip.

Fig. 15 is a side view of the feed rolls carrying the grand total consecutive number device. Fig. 16 is a detail view of the motor and a part of the driving connections. Fig. 17 is a partial plan view of the record strip. 60 Figs. 18, 19 and 20 are detail views of the tickets issued by the machine.

Described in general terms the machine comprises a rotatable drum having spirally mounted thereon a plurality of destination 65 devices, any one of which is arranged to be brought into co-operative relation with ticket issuing and registering mechanisms. This drum is provided with a spiral axis which as said drum is rotated shifts the drum and 70 destination devices carried thereby axially. An indicating device is provided which is driven by the rotation of the drum and is arranged to display the destination device that is in co-operative relation with the ticket 75 issuing and registering mechanisms. When the proper destination device is positioned, a switch lever is operated which throws on the current to the motor for the operating mechanism, during the operation of which 80 the positioned destination device is first partially depressed and while in this partially operated position, it is inked by suitable mechanism driven by the motor operating mechanism. This latter mechanism also operates the feeding devices for the ticket strip so as to bring the strip upon the platen adjacent to the partially operated destination device, after which the operating mechanism will complete the operation of the destination device and stamp the ticket with the fare, the destination, and the number of 85 tickets issued thereto. A severing mechanism is also provided which is driven by the operating mechanism to sever that portion 90 of the ticket strip bearing the fare, the destination and the number of tickets issued thereto from the remainder of the strip, which ticket will then be handed to the patron. By a suitable inking ribbon the 95 information recorded upon the ticket is also transferred to the record strip which is stored within the machine. Each destination device is provided with amount determining fingers which when said device is 100 operated actuates a registering mechanism an extent corresponding to the fare represented by the operated destination device. Near the end of the operation of the machine the motor circuit is automatically 105 110

broken and the parts arrested at the end of a complete operation. With this brief outline of the operation of the machine and the functions performed thereby a detail description of the various parts which go to make up the machine will now be given.

A drum 1 provided with a spiral axis 2 is mounted in the head of a frame work 3. This drum has mounted thereon a plurality 19 of destination devices 4 which are arranged spirally upon said drum. As the drum is rotated, its spiral axis 2 will shift said drum axially so as to bring any desired destination device 4 into coöperative relation with the 15 ticket issuing and registering mechanisms hereinafter more particularly described.

Each of the destination devices 4 (Figs. 1, 7, 8 and 10) is provided with a head 5 carrying a consecutive numbering device 6 20 and amount determining fingers 7, the former being arranged to stamp upon the issued ticket the number of tickets stamped by that particular destination device, while the amount determining fingers are arranged to 25 actuate the registering mechanism an extent corresponding to the fare to the destination represented by said device. The printing face of the head 5 of a destination device carries type 1000, as clearly shown in Fig. 30 10, for printing the name of the destination station on the tickets together with the fare. Projecting inwardly from each destination device is a pair of rods 8 which are guided at their inner ends by a tube 9 mounted 35 within the drum 1, while the outer end of said rods are guided by recesses 10 formed upon the surface of the drum. The rods 8 are provided with collars 11 which abut against the outer surface of the tube 9, and 40 against which the inner ends of coiled springs 12 surrounding said rods abut while the outer ends of said springs abut against the inner surface of the outer shell forming the drum proper. By these springs 12 each 45 destination device is held in the position shown in Fig. 1 of the drawings. Each of these devices is also provided with an inwardly extending rod 13 which is arranged to be brought beneath an actuating plunger 50 14 (Figs. 1, 12 and 13) which is mounted within the head 15 of an arm 16 extending from the main frame work 3. At the beginning of the operation of the operating mechanism, the plunger is partially depressed, by which the positioned destination 55 device is also partially depressed and near the end of the operation of said mechanism the plunger is completely depressed which in turn completes the operation of the partially 60 operated destination device. The drum 1 is provided with a railing 17 by which the attendant may rotate the drum. An arm 18 extending upwardly from the arm 16 of the main frame is provided with 65 roller bearings 19 upon which a tube 20

forming the center of the drum rotates. The rearward plate of said drum is also provided with roller bearings 21 which as the drum is revolved roll upon a portion of the frame work 3. The purpose of these roller bearings as is obvious is to provide for the 70 easy rotation of the drum.

Extending rearwardly from the spiral axis 2, is a shaft 22 (Fig. 1) to which is splined a pinion 23. This pinion 23 meshes 75 with a gear 24 secured to one end of a stub shaft 25 mounted in the main frame 3. At its other end this stub shaft is provided with a gear 26 which meshes with a similar gear 27 secured to an indicator disk 28 (Figs. 1 80 and 3) loosely mounted upon the shaft 22. The above described gear connection between the drum and the indicating disk, as it will be seen by reference to Fig. 1, is so proportioned that a full rotation of the 85 drum 1 will impart only a quarter rotation of the disk 28. This disk 28 has near its outer edge the different destination points from the issuing office stamped thereon, as shown in Fig. 3 of the drawings. In this 90 figure the disk is divided into two classes of fare, namely, half fare and full fare, with the names of the destinations upon said disk duplicated. The drum 1 is of course provided with as many destination devices 4 as 95 there are destination points upon the indicator 28 and these destination points on the indicator are in such relation with the destination devices 4 that when any one of the latter is in coöperative relation with the 100 ticket issuing and registering mechanisms the corresponding destination point is displayed by the indicator disk 28. It is of course to be understood that the amount determining fingers 7 carried by the "half 105 fare" destination devices will actuate the registering mechanism half the extent only as will the corresponding destination devices of the "full fare" class. The "half fare" destination devices are also provided 110 with the characters "1/2" which are printed in connection with the destination, the number of tickets issued thereto and the fare upon the ticket, Fig. 19, and the record strip for the purpose of distinguishing the 115 "half fare" tickets from the "whole fare" tickets. A bell crank member 30 (Fig. 3) is mounted upon the frame work 3 and the end of the horizontal member of said bell crank is provided with an arrow head 31 which as 120 the disk 28 is rotated, points to the different destination devices that are brought into coöperative relation with the actuating plunger 14. The outer edge of the disk 20 is serrated and is provided with notches 32 into which enters a spring-pressed plunger 33 carried by an arm 34 secured to a portion of the frame work 3. This plunger is for the purpose of preventing accidental 125 displacement of the disk 28 and the drum 1. 130

and also to insure proper alinement between the actuating plunger 14 and the positioned destination device 4.

Having brought the desired destination device into coöperative relation with the actuating plunger 14, a switch lever 35 (Fig. 1) is drawn outwardly, by which movement a three prong lever 36 is rocked in a clockwise direction, swinging contacts 37 carried by the prong 38 of the lever 36 into engagement with the contacts 39 formed upon a stationary plate 40 secured to the frame work of the machine. These contacts 37 and 39 are then held in engagement by a spring pressed plunger 41 which engages with one of a pair of notches 42 formed upon the hub of the member 36. As the contacts 37 and 39 are brought into engagement the circuit for the motor 43 (Fig. 16) is closed. The armature shaft 44 of the motor is provided with a worm 45 (Figs. 1 and 16) which meshes with a worm gear 46 secured near the outer end to one of the drive shafts 47 of the machine. This drive shaft is provided with a mutilated beveled gear 48 which drives a beveled gear 49 secured to the lower end of a shaft 50 which shaft at its upper end is provided with a beveled pinion 51. This last mentioned pinion meshes with a similar pinion 52 secured to the rear end of a shaft 53 which at its forward end is provided with a disk 54 (Figs. 12 and 13). This shaft 53 extends through the arms 18 and the frame work 3 and the disk 54 is secured to the outer end thereof and has extending therefrom a roller 55 which plays in an elongated slot 56 formed in the upper end of the plunger frame 14. By reference to Fig. 16 it will be seen that a portion of the teeth of the mutilated gear 48 is normally in engagement with the teeth of the gear 49 so that as the motor circuit is closed and the gear 48 is driven in the direction of the arrow shown in Fig. 16, the beveled gear 49 will be partially rotated and through the shaft 50, beveled pinions 51 and 52 and shaft 53, rotate the disk 54 and through the roller 55 carried thereby partially lower the actuating plunger 14 which in turn partially depress the destination device in coöperative relation therewith against the tension of its springs 12. In this partially operated position of the destination device, the inking mechanism hereinafter described will be operated to ink the partially operated destination device.

The shaft 47 at its extreme rearward end (Fig. 16) is provided with a finger 57 which is normally engaged by the upper end of an arm 58 secured to a stub shaft 59 suitably mounted upon the motor frame. This stub shaft has also secured thereto an arm 60 to the free end of which is connected the lower end of a link 61, the upper end of the latter being secured to the prong 62 of the lever

36 (Fig. 1). As the switch lever 35 is moved forwardly to close the motor circuit, as previously described, the link 61 will be moved upwardly, by which movement the arms 58 and 60 will be rocked in a clockwise direction (Fig. 16) thereby withdrawing the arm 58 from engagement with the finger 57 secured to the driving shaft 47. This withdrawal of the arm 58 from engagement with the finger 57 occurs substantially simultaneously with the closing of the motor circuit so that the parts driven by the motor may then be free to be operated. The shaft 50 has secured thereto approximately at its center a disk 63 which is provided with a camming lug 64. This lug near the end of the rotation of the shaft engages with the lug 65 formed upon the upper edge of the prong 62 and cams said prong downwardly or in an anticlockwise direction (Fig. 1) thereby withdrawing the contacts 37 carried by the prongs 38 from engagement with the contacts 39, thus breaking the motor circuit. As the prong 62 is cammed downwardly, the link 61 will also move downwardly and through the arm 60 and shaft 59 rock the upper end of the arm 58 into the path of the finger 57 and thus arrest the parts when the same reach their normal position. The mutilated gear 48 is provided with a sufficient number of teeth so that for each complete rotation of said gear a full rotation will be imparted to the gear 49 and shaft 50, the latter through gears 51 and 52 rotating shaft 53. That portion of the gear 48 having the teeth cutaway is so designed as to lock the gear 49 and parts connected therewith while said cutaway is passing the gear 49.

The main frame 3 has extending forwardly therefrom a platform 66 upon which is rigidly mounted an auxiliary frame 67 supporting the ticket issuing and registering mechanisms. A ticket roll 68 (Fig. 2) is supported as at 69 upon the auxiliary frame 67 and the strip from this roll is led over an idler 70 between rollers 71, 72, 73 and 74. The roller 71 is provided with an electro plate for printing any suitable information upon the face of the ticket, as shown in Fig. 18 while the roller 72 is provided with devices for printing the date and the issuing station upon the back of the ticket, as shown in Fig. 20. The roller 73 is provided with numbering devices for printing upon the ticket the total number of tickets issued from the station where the machine is located, which total number is shown at 75 upon the face of the ticket 76 shown in Fig. 18. This numbering device comprises a plurality of wheels 77 suitably mounted in the roller 73, the units wheel of which is arranged to be advanced one step upon each rotation of the roller. A stationary plate 78 is mounted in the auxiliary frame work 67, Fig. 15, and

this plate is provided with a cam groove 79 in which plays a roller 80, Fig. 14, projecting from one end of an arm 81. This arm at its other end is connected to an arm 82 supported upon a shaft 83 carrying the numbering wheels 77 and at its free end is provided with a pawl 84 for engaging the teeth of a ratchet 85 secured to the units wheel 86. As the roller 73 is rotated, the cam groove 79 formed in the stationary plate will reciprocate the link 81, thereby rocking the arm 82 so as to advance the units wheel of the consecutive numbering device one step. A suitable transfer mechanism is provided between the units wheel and the wheels of higher denomination, which transfer mechanism may be any of the forms well known in the art.

Each of the above mentioned rollers is provided with a pinion 87, the pinions of the rolls 71 and 72 meshing, while the pinions of the rolls 73 and 74 also mesh. The pinions connected to the rollers 72 and 74 mesh with a pinion 88 (Fig. 2), which pinion has secured thereto a beveled gear 89 which meshes with a similar gear 90 secured to the upper end of an inclined shaft 91. This shaft is suitably mounted upon the auxiliary frame work 67 and at its lower end is provided with a beveled pinion 92 which meshes with a similar gear 93, that is secured to a pinion 94 suitably supported in the auxiliary frame work 67. This pinion 94 meshes with a similar pinion 95 (Fig. 1), which pinion is secured to the upper end of a stub shaft 96, which at its lower end is also provided with a beveled gear 97 that meshes with a similar gear 98 secured to the forward end of the aforesaid driving shaft 47. By the above described gear connections, the rollers 71 to 74, inclusive, will be given a complete rotation at each operation of the machine. By reference to Fig. 14, it will be seen that the rollers 71 and 74 are provided with enlarged portions 99, by which portions the ticket strip is gripped between each pair of rollers and fed forwardly prior to the complete rotation of said rollers. From the rollers the ticket strip is fed between knives 100 and 101 which forms the severing mechanism for the strip and thence on to a platen 102 mounted in the auxiliary frame work 67.

From the above description it will be seen that the ticket strip will be fed upon the platen 102 prior to the complete rotation of the drive shaft 47 and will remain in such position during the remainder of rotation of said drive shaft in order to receive an impression from the operated destination device, at which time the severing mechanism, comprising the knives 100 and 101 is operated to sever that portion of the ticket strip having the destination recorded thereon so that same may be handed to the patron.

The knife 101 is rigidly mounted upon the

auxiliary frame work 67 (Fig. 9) while the knife 100 is pivotally mounted, as at 103, to one of the sides of said frame work. This latter knife beyond its pivotal point has connected thereto the upper end of a link 104 supported at its lower end by a rod 105, the latter being suitably guided upon the auxiliary frame work. This rod 105 near its lower end carries a disk 106 with the under side of which a roller 107 supported by an arm 108 secured to the shaft 91 engages near the end of rotation of said shaft and thereby elevates the rod 105 and through link 104 rocks the knife 100 about its pivotal point 103 so as to sever the portion of the ticket strip resting upon the platen 102 and containing the destination from the remainder of said strip.

As previously described, the destination device 4 that is in coöperative relation with the reciprocating member 14 is partially depressed upon the beginning of rotation of shaft 53 and in this partially depressed position, the destination device is arranged to be inked by an ink roller 109 (Figs. 2 and 6) supported in arms 110 pivotally mounted upon a cross rod 111, which in turn is supported by arms 112 pivotally mounted as at 113 to the auxiliary frame 67. The roller 109 normally rests upon a disk 114 carrying a supply of ink. This disk is mounted upon a vertical stud 115 extending up from one of the cross arms of the auxiliary frame 67. This disk 114 has connected thereto a gear 116 which is arranged to be rotated by a pawl 117 carried by an arm 118 pivotally mounted upon the stud 115. The arm 118 is connected to one end of a link 119 the other end of which passes through a stud 300 secured to one of the arms 112. This link 119 is provided with a collar 301, with which the stud 300 contacts as the arm 112 carrying said stud nears the end of its movement in a counter clockwise direction, Fig. 2, and thereby move the link and through the above described connection partially rotate the gear 116 and the inking disk 114 connected thereto. As the arm 112 carrying the stud 300 is returned to normal position the stud will contact with a collar 302 secured to the link 119 and restore said link and parts connected thereto to normal position. As it is not necessary that the feed device for inking disk 114 receive as great a movement as the inking roll 109, the above described lost motion between the stud 300 carried by one of the arms 112 and the collars 301 and 302 secured to the link 119 is provided. From this it will be seen that as the arms 112 are oscillated, as previously described, the inking disk 114 will be partially operated through its connection with the gear 116. The rotation of the inking disk 114 is for the purpose of furnishing a fresh supply of ink to the roller 109 as said roller

is reciprocated across the disk. One of the arms 112 is connected by a link 120, (Figs. 2 and 2^a), to a ring 121 surrounding a disk 122 eccentrically mounted upon the afore-
5 said shaft 91. The eccentrically mounted disk 122 is so located upon the shaft that upon the very beginning of rotation of said shaft, the arms 112 through the link 120 (Fig. 2), will be rocked in an anti-clockwise direction carrying the roller 109 over the feed rollers 71 and 73 and thence into contact with the destination stamp 123 that is in partially operated condition. By this movement the ink roller 109 inks the feed
10 rollers 71 and 73 carrying an electroplate and the total consecutive numbering devices respectively, and also inks the partially operated destination device. In its movement to ink the destination device, the roller 109 is guided by its supporting rod 124 passing into an elongated slot 125 formed upon a guide bracket 126 secured to the auxiliary frame 67. The purpose of this guide bracket 126 is two fold: first, to insure the
15 inking of the partially operated destination device, and second, to prevent the dropping of the roller 109 into contact with the knife 100 or the platen 102.

Each of the arms 110 supporting the ink roll 109 has an extension 127 to which a rod 128 is pivotally attached, Figs. 2 and 6. The rods 128 at their lower ends are guided by lugs 129 projecting from arms 112 and intermediate their ends the rods are provided with collars 130. Springs 131 are interposed between the collars 130 and lugs 129 and thus hold the ink roll under spring tension into contact with the inking disk 114.

40 A summary record strip 131 is mounted upon the auxiliary frame 67 and is arranged to be fed from a supply roll 132 over a guide roll 133, between the feed rollers 73 and 74, around a guide roll 134 and thence over the platen 102 to a storage roll 135 supported by the auxiliary frame 67. An inking ribbon 136 is led from a roll 137 around a guide roll 138 between the feed rollers 71, 72, 73 and 74 around the guide roll 134 thence over the platen 102 to a roll 139 mounted in the auxiliary frame 67.

When the partially operated destination device is completely operated to stamp the fare, the destination and the number of tickets issued thereto upon the ticket strip, the same information is transferred to the record strip 131 through the inking ribbon 136, (Fig. 2). The record strip and the inking ribbon passing between the rolls 73 and 74 will be fed by said rolls and the amount of strip and ribbon fed thereby will be stored upon the rolls 135 and 139 respectively, by suitable friction devices, not shown, but which are well known in the art.

65 As each destination device is operated to

stamp the ticket and the record strip its numbering device will be advanced one unit by its companion pawl 200, Fig. 11, which is mounted upon the drum 1 and arranged to engage with the teeth of a ratchet 201 connected to the units wheel of its companion numbering device 6. When a destination device is depressed the ratchet 201 is lowered with the device independently of the pawl 200 and the pawl engages above the next succeeding tooth so that upon return of the destination device to normal position the pawl 200 causes the units wheel to rotate one step forwardly to add one on the counter. A retaining pawl 202 holds the units wheel in its advanced position. No transfer devices between the units wheel and the remaining wheels of the numbering devices are shown it being understood that any of the well known devices may be employed.

The record strip 131 is inclosed in a suitable casing and is only accessible to the auditor or some other authorized person. As the number of tickets issued to any destination is recorded upon the record strip adjacent to the destination recorded thereon, it is obvious that by means of this strip a quick and accurate audit may be obtained without interfering in the least with the operation of the machine, all being necessary is to detach the used portion of strip from the storage roll 135. Each machine is provided with a hand stamp 140, which as herein shown is mounted upon the arm 141, (Fig. 2). Upon the removal of the used portion of the record strip by the proper person one end thereof is inserted in the stamp 140 and the latter operated by which operation suitable characters, (Fig. 17), are recorded upon the strip for the purpose of identifying the machine from which it was removed.

As heretofore stated, a registering mechanism is provided for accumulating the total of the fares of the issued tickets, which mechanism will now be described.

Each destination device, as previously described, is provided with amount determining fingers 7 (Figs. 1, 2, 7 and 8). These fingers are graduated and represent the fare from the issuing station to the destination represented by the device carrying said fingers. One finger 7 is provided for each denomination represented in the fare charged. For example if a destination device prints a 25c ticket but two fingers will be employed whereas another destination device printing a \$3.25 ticket would have three fingers. As the selected destination device is lowered, the amount determining fingers 7 carried thereby will come in contact with vertical links 142 supported by arms 143 and 144 (Figs. 2 and 5). The arms 143 are pivotally mounted upon an upright 145 of a frame 146 which is secured to the platform 66 extend-

130

ing forwardly from the main frame 67, of the machine. The arms 143 have extensions 147 (Figs. 2 and 5), which extensions are normally drawn into contact with lugs 148 by springs 149 suitably secured to the extensions and to the upright 145. The purpose of the lugs 148, as is obvious, is to prevent the return of the arms 143 and the vertical links supported thereby beyond their normal position. The arms 144 supporting the lower ends of the links 142 are connected to the ends of a shaft 150 and sleeves 151 surrounding said shaft, the other ends of the sleeves and shaft having secured thereto arms 152 which support at their outer ends pawls 153 that are spring pressed into engagement with gear wheels 154. The gear wheels 154 are loosely mounted upon the shaft 150 and sleeves 151 and mesh with pinions 155 secured to registering wheels 156.

As the amount determining fingers 7 carried by the different destination devices are of different lengths, it will be seen that when said destination devices are lowered, the links 142 will have imparted thereto a graduated movement, which movement through the shaft 150 and sleeves 151 and pawls 153 carried by arms 152 will be imparted to the wheels 154 and by the latter to the registering wheels 156. As the operated destination device is returned to its normal position, the parts actuating the registering mechanism will also be returned to their normal position by the springs 149 during which movement the pawls 153 will ride idly over the gears 154, the latter and the registering wheels being held in their adjusted positions by plungers 157 which engage with recesses formed in flanges 158 of said registering wheels 156. In the illustrative form of embodiment disclosed herein but three gear wheels 154 are shown. It is obvious, however, that the machine may be provided with more or less gear wheels the number of gears being dependent upon the number of fingers 7 carried by the destination device issuing tickets of the largest denomination. No transfer mechanism is shown between the various elements of the registering mechanism, as any of the well known forms may be used. The registering mechanism is inclosed in a casing 159, the said casing being provided with a hinged portion 160 which portion covers the registering wheels and is under lock and key so access may be had to it only by a duly authorized person. Partly surrounding the wheels 156 is a shield 162 having a slot 163 through which the figures on the registering wheels may be read when the hinged portion 160 of the casing is raised. The casing 159 is further provided with openings 161 through which the upper ends of the links 142 extend.

While the form of mechanism herein shown and described is admirably adapted to fulfil the objects primarily stated, it is to be understood that it is not intended to confine the invention to the one form of embodiment shown and described herein, as it is susceptible of embodiment in various forms, all coming within the scope of the claims which follow.

What is claimed is:

1. In a machine of the class described, the combination with a registering mechanism, of a rotatable drum having mounted thereon a plurality of destination devices, means for axially shifting said drum as it is rotated whereby any destination device may be brought into coöperative relation with the registering mechanism, and mechanism for operating the destination device in coöperative relation with the registering mechanism whereby the latter mechanism will be actuated by the operated destination device. 75

2. In a machine of the class described, the combination with a registering mechanism, of a rotatable drum having mounted thereon a plurality of destination devices, means for axially shifting said drum as it is rotated whereby any destination device may be brought into coöperative relation with the registering mechanism, amount determining fingers carried by each destination device, and mechanism for operating the destination device in coöperative relation with the registering mechanism whereby the latter mechanism will be actuated by the amount determining fingers of the operated destination device. 90

3. In a machine of the class described, the combination with a registering mechanism, of a rotatable drum having mounted thereon a plurality of destination devices, means for axially shifting said drum as it is rotated whereby any destination device may be brought into coöperative relation with the registering mechanism, means for indicating the destination device in coöperative relation with the registering mechanism, and means for actuating the registering mechanism by the destination device in coöperative relation therewith. 195

4. In a machine of the class described, the combination with a registering mechanism, of a rotatable drum having mounted thereon a plurality of spirally arranged destination devices, means for axially shifting said drum as it is rotated whereby any destination device may be brought into coöperative relation with the registering mechanism, a reciprocatory member for actuating the registering mechanism by the destination device in coöperative relation therewith, and a motor and connections for operating the reciprocatory member. 120

5. In a machine of the class described, the combination with a registering mecha- 130

nism, of a rotatable drum having mounted thereon a plurality of spirally arranged destination devices, means for axially shifting said drum as it is rotated whereby any destination device may be brought into coöperative relation with the registering mechanism, means for indicating the device in such relation, amount determining fingers carried by each device, and a motor and connections for actuating the registering mechanism by the amount determining fingers of the destination device in coöperative relation with said mechanism.

6. In a machine of the class described, the combination with a registering mechanism, of a rotatable drum having mounted thereon a plurality of spirally arranged destination devices, means for axially shifting said drum as it is rotated whereby any destination device may be brought into coöperative relation with the registering mechanism, means for indicating the device in such relation, a motor and connections for actuating the registering mechanism by the 20 destination device in coöperative relation with said mechanism, a normally open circuit for said motor, means for closing the circuit, and means controlled by the motor connections for opening said circuit when the registering mechanism is actuated.

7. In a machine of the class described, the combination with a registering mechanism, of a rotatable drum having mounted thereon a plurality of destination devices, means for axially shifting said drum as it is rotated whereby any destination device may be brought into coöperative relation with the registering mechanism, and means for actuating the registering mechanism by the 35 destination device in coöperative relation therewith, the said device also recording upon a record strip the destination and the fare theroeto.

8. In a machine of the class described, the combination with a registering mechanism of a rotatable carrier having spirally mounted thereon a plurality of destination devices, means for axially shifting said drum as it is rotated whereby any destination device 50 may be brought into coöperative relation with the registering mechanism, and means controlled by each destination device for entering upon the registering mechanism the amount of fare to said destination and also 55 for recording upon a record strip the destination device used and the number of times it has been used.

9. In a machine of the class described, the combination with a ticket issuing mechanism, of a rotatable drum having mounted thereon a plurality of destination devices, means for axially shifting said drum as it is rotated whereby any destination device may be brought into position to stamp the destination represented thereby upon a ticket,

and means for operating the positioned destination device.

10. In a machine of the class described, the combination with a ticket issuing mechanism, of a rotatable drum having mounted thereon a plurality of destination devices, a numbering mechanism carried by each device, means for axially shifting said drum as it is rotated whereby any destination device may be brought into position to stamp 70 the destination represented thereby and the number of tickets issued thereto upon a ticket, and means for operating the positioned destination device.

11. In a machine of the class described, the combination with a ticket issuing mechanism, of a rotatable drum having mounted thereon a plurality of destination devices, means for axially shifting said drum as it is rotated whereby any destination device 75 may be brought into position to stamp the destination represented thereby upon a ticket, and means for operating the positioned destination device and the ticket issuing mechanism.

12. In a machine of the class described, the combination with a ticket issuing mechanism, of a rotatable drum having mounted thereon a plurality of destination devices, means for axially shifting said drum as it 90 is rotated whereby any destination device may be brought into position to stamp the destination represented thereby upon a ticket, an inking mechanism for the destination devices, and means for operating the inking mechanism and the positioned destination device.

13. In a machine of the class described, the combination with a ticket issuing mechanism, of a rotatable drum having mounted thereon a plurality of destination devices, means for axially shifting said drum as it is rotated whereby any destination device may be brought into position to stamp the destination represented thereby upon a 100 ticket, an inking mechanism for the destination devices, and means for operating the inking mechanism and the positioned destination device, the said operating means being so constructed as to first, partially depress the destination device to be operated, second, ink the partially operated destination device and then complete the operation of said destination device.

14. In a machine of the class described, the combination with a rotatable drum having mounted thereon a plurality of destination devices, means for axially shifting said drum as it is rotated whereby any desired destination device may be brought into a common printing position, means for feeding a ticket strip to the common printing position, mechanism for severing the strip into tickets, and means for operating the 110 destination device in printing position, the 115

strip feeding means and the mechanism for severing the strip into tickets.

15. In a machine of the class described, the combination with a rotatable drum having mounted thereon a plurality of destination devices, of a platen, means for axially shifting said drum as it is rotated whereby any desired destination device may be brought into coöperative relation with the platen, means for feeding a ticket strip between the platen and the destination device in coöperative relation therewith, means for bringing the platen and the destination device in coöperative relation therewith together for the purpose of taking an impression upon the strip, and mechanism operated by said means for severing that portion of the strip bearing the impression from the remainder of the strip.
20. In a machine of the class described, the combination with a rotatable drum having mounted thereon a plurality of destination devices, of a numbering mechanism carried by each device, a platen, means for axially shifting said drum as it is rotated whereby any desired destination device may be brought into coöperative relation with the platen, means for feeding a ticket strip between the platen and the destination device in coöperative relation therewith together for the purpose of recording upon the strip the destination and number of tickets issued thereto, and mechanism operated by said means for severing that portion of the strip bearing the impression from the remainder of the strip.

17. In a machine of the class described, the combination with a rotatable drum having mounted thereon a plurality of destination devices, of a platen, means for axially shifting said drum as it is rotated whereby any desired destination device may be brought into coöperative relation with the platen, means for feeding a ticket strip and a record strip between the platen and the destination device in coöperative relation therewith, means for causing a relative movement between the platen and the selected destination device for the purpose of recording upon the ticket and record strips the destination represented by the device in coöperative relation with the platen.

55. 18. In a machine of the class described, the combination with a rotatable drum having mounted thereon a plurality of destination devices, of a numbering mechanism carried by each device, a platen, means for axially shifting said drum as it is rotated whereby any desired destination device may be brought into coöperative relation with the platen, means for feeding a ticket strip and a record strip between the platen and the destination device in coöperative relation

therewith, and means for causing a relative movement between the platen and the selected destination device for the purpose of recording upon the ticket and record strips the destination represented by the device in coöperative relation with the platen and the number of tickets issued to said destination.

19. In a machine of the class described, the combination with a rotatable drum having mounted thereon a plurality of destination devices, of a platen, means for axially shifting said drum as it is rotated whereby any desired destination device may be brought into coöperative relation with the platen, means for feeding a ticket strip and a record strip upon the platen, and means for moving the selected destination device into contact with the platen for the purpose of recording upon the ticket and record strips the destination represented by the device in coöperative relation with the platen.

20. In a machine of the class described, the combination with a rotatable drum having mounted thereon a plurality of destination devices, of a numbering mechanism carried by each device, a platen, means for axially shifting said drum as it is rotated whereby any desired destination device may be brought into coöperative relation with the platen, means for feeding a ticket strip and a record strip upon the platen, and means for moving the selected destination device into contact with the platen for the purpose of recording upon the ticket and record strips the destination represented by the device in coöperative relation with the platen, and means for severing that portion of the ticket strip bearing the destination from the remainder of the strip.

21. In a machine of the class described, the combination with a rotatable drum having mounted thereon a plurality of destination devices, of registering and ticket issuing mechanisms, means for axially shifting said drum as it is rotated whereby any destination device may be brought into coöperative relation with the registering and the ticket issuing mechanisms, and means for operating the destination device in coöperative relation with the registering and the ticket issuing mechanisms whereby a ticket will be issued and the fare therefor registered.

22. In a machine of the class described, the combination with a rotatable drum having mounted thereon a plurality of destination devices, of registering and ticket issuing mechanisms, means for axially shifting said drum as it is rotated whereby any destination device may be brought into coöperative relation with the registering and the ticket issuing mechanisms, means for operating the device in such relation, and mechanism carried by the operated device for stamping a ticket with the destination and for registering the fare for said ticket.

23. In a machine of the class described, the combination with a rotatable drum having mounted thereon a plurality of destination devices, of registering and ticket issuing mechanisms, means for axially shifting said drum as it is rotated whereby any destination device may be brought into coöperative relation with the registering and the ticket issuing mechanisms, means for operating the device in such relation, and mechanism carried by the operated device for stamping a ticket with the destination and the number of tickets issued thereto and for registering the fare of each ticket issued.
24. In a machine of the class described, the combination with a rotatable drum having mounted thereon a plurality of destination devices, of registering and ticket issuing mechanisms, means for axially shifting said drum as it is rotated whereby any destination device may be brought into coöperative relation with the registering and the ticket issuing mechanisms, means for indicating the device in such relation, and mechanism for operating the destination device in coöperative relation with the registering and the ticket issuing mechanisms whereby a ticket will be issued and the fare therefor registered.
25. In a machine of the class described, the combination with a rotatable drum having mounted thereon a plurality of destination devices, of means for axially shifting said drum as it is rotated whereby any destination device may be brought into a common position, means for feeding a ticket strip to the common position, a registering mechanism, and an operating mechanism for the ticket feeding means constructed to actuate also the destination device brought to the common position whereby a portion of the ticket strip will be stamped with the destination represented by the operated device and the fare thereto registered.
26. In a machine of the class described, the combination with a rotatable drum having mounted thereon a plurality of destination devices, of means for axially shifting said

drum as it is rotated whereby any destination device may be brought into a common position, a registering mechanism constructed to be actuated by the devices when they are brought into the common position, inking mechanism for the destination devices, feeding means for a paper strip, mechanism for severing the strip into checks, and an operating mechanism so constructed as to operate the feeding means for the paper strip and partially to operate the destination device, in which position the latter device will be inked by the inking mechanism, and thereafter complete the operation of the partially operated device for the purpose of stamping the paper strip with the destination and actuating the registering mechanism, and finally to sever that portion of the strip bearing the destination.

27. In a machine of the class described, the combination with a rotatable drum having mounted thereon a plurality of destination devices, of spring means for retaining the destination devices in normal position on the drum, a reciprocatory member for operating the destination devices, and means for axially shifting said drum as it is rotated whereby any destination device may be brought into position to be operated by said operating member.

28. In a machine of the class described, the combination with a rotatable drum having mounted thereon a plurality of destination devices, of spring means for retaining the destination devices in normal position on the drum, a reciprocatory member mounted within the drum for operating the destination devices, and means for axially shifting said drum as it is rotated whereby any destination device may be brought into position to be operated by said operating member.

In testimony whereof I affix my signature in the presence of two witnesses.

CHARLES FORTH.
